THREE-DIMENSIONAL PUZZLE

Arthur Harris, Brooklyn, N. Y.

Application November 18, 1947, Serial No. 786,635

3 Claims. (Cl. 273—160)

1

The present invention relates to a new article of manufacture useful as a puzzle.

The puzzle of this invention comprises a plurality of members capable of interlocking with one another by a combination of twisting and sliding motions to form a symmetrical and self-supporting unit. The embodiment specifically disclosed herein comprises twelve members of equal length and cross-section.

The members of the puzzle may be made of any suitable material such as wood, metal, translucent or multi-colored synthetic plastics, or the like. The puzzle is useful as a game, as a source of self-entertainment and as a mechanical aptitude test.

An advantage of the present invention is that the members of the puzzle may easily be machined to the proper size and configuration and that they include no more than five different shapes.

This and further advantages, as well as the utility, of the invention will appear from the following description made with reference to the accompanying drawing wherein:

Figure 1 is an isometric view of the preferred embodiment of the puzzle in its completely assembled form;

Figure 2 is an isometric view showing the relative positions of the first five members assembled;

Figure 3 is an isometric view showing the configuration of two of the members;

Figure 4 is an isometric view showing the configuration of four of the members;

Figure 5 is an isometric view showing the configuration of two other of the members;

Figure 6 is an isometric view showing the configuration of two more of the members; and

Figure 7 is an isometric view showing the configuration of the remaining two members.

For convenience in describing the manner in which the members of the puzzle are assembled to form the symmetrical self-supporting unit illustrated in Figure 1, the various members are designated by reference numerals 11 to 22, inclusive. Members 21 and 22 are identical with one another and are formed as shown in Figure 3, members 12, 13, 15, and 18 are identical with one another and formed as shown in Figure 4, members 11 and 17 are identical with one another and formed as shown in Figure 5, members 14 and 16 are identical with one another and formed as shown in Figure 6 and members 19 and 20 are identical with one another and formed as shown in Figure 7.

Each of the members 11 to 22 inclusive has

a middle portion 25, two end portions 26, and two recessed portions. The middle portions of the members are of equal length, the end portions are preferably, but not necessarily, of equal length, and each of said portions has a square cross-section.

Members 12, 13, 15, 18, 21 and 22 are each provided with two large recesses 27 that are wide enough to fit snugly over the middle portions 25 or end portions 26. Members 21 and 22 are further provided with two small recesses 28 and each of the members 12, 13, 15 and 18 are provided with two small recesses 28'. Members 11, 14, 16, and 17 each have one large recess 27 and a small recess 28' between the middle portion 25 and one end portion 26 and a cylindrical section 29 between the middle portion 25 and the other end portion 26, the members 11 and 17, however, being opposites of the members 14 and 16.

20 The members 19 and 20, illustrated in Figure 7, are each provided with two cylindrical portions 29 as shown.

It will become apparent, from a consideration of the configurations illustrated in Figures 3 to 7, inclusive, that the recessed portions, of which there are twenty-four in the twelve members, are of only three distinct types and that of these three, two are optical opposites. As a result, the equipment and operations required to shape the component members are kept to a minimum and the puzzle can be produced at low cost.

The members of the puzzle are assembled into the form shown in Figure 1 by proceeding in the following manner, it being understood, of course, that the relative positions of the various members may be checked at any time by reference to Figures 1 and 2 of the drawing.

40 The cylindrical portion 29 of member 11 is engaged with the inner corner of a large recess 27 of the member 12, the large recesses 27 of said member 12 facing in an upwardly direction and the small recesses 28' facing outwardly. A large recess 27 of the member 13 is slipped over the outer portion 26 of the member 11 adjacent the engaged cylindrical portion 29 and slid toward member 12 until it enters the plane of member 12. The member 11 is then given a quarter turn clockwise to securely lock members 11, 12 and 13 into the position shown in Figure 2.

45 The cylindrical portion 29 of the member 14 is then engaged with the inner corner of the other large recess 27 in member 12, a large recess 27 of the member 15 is slipped over the outer portion 26 of the member 14 protruding beyond the member 12, and member 14 is slid toward the

55 member 12, and member 14 is slid toward the

member 12 until it enters the plane of members 12 and 13. Member 14 is then given a quarter turn counter-clockwise to securely lock members 14 and 15 in place. At this point the five members thus far assembled appear as shown in Figure 2.

The cylindrical portion 29 of the member 16 is engaged with the inner corner of the large recess 27 remaining open in the member 13 and the cylindrical portion 29 of the member 17 is in like manner engaged with the inner corner of the large recess 27 remaining open in member 15. The two large recesses 27 of the member 18 are then slipped over the middle portions 25 of members 16 and 17 with the small recesses 28 of member 18 adjacent members 13 and 15. The member 18 is then slid along members 16 and 17 until it enters the plane of members 12, 13 and 15. Member 16 is given a quarter of a turn clockwise and member 17 is given a quarter of a turn counter-clockwise.

The cylindrical portions 29 of the member 19 are engaged with the inner corners of the large recesses 27 remaining open in members 11 and 16 and cylindrical portions 29 of the member 20 are engaged with the inner corners of the large recesses 27 remaining open in the members 14 and 17. The two large recesses 27 of the member 21 are slipped over the protruding end portions 26 at the tops of members 19 and 20, the small recesses 28 of said member 21 facing downwardly and the member 21 is slid toward members 16 and 17 until it enters the plane of members 16, 17, and 18. The two large recesses 27 of the member 22 are slipped over the protruding end portions 26 at the bottoms of members 19 and 20, the small recesses 28 of the member 22 facing upwardly. The member 22 is then slid upwardly until it enters the plane of members 11, 12, and 14. Finally member 19 is given a quarter turn clockwise and member 20 is given a quarter turn counter-clockwise to form the symmetrical, self-sustaining unit illustrated in Figure 1, and having four horizontal members 11, 14, 16, and 17, four members 12, 18, 21, and 22 transverse to the horizontal members, and four vertical members 13, 15, 19, and 20.

It is to be understood, of course, that numerous modifications and alterations will become apparent at once to those skilled in the art upon reading the description herein. Thus, for example, members 11, 14, 16, and 17 may be extended beyond the end portions 20 adjacent the cylindrical portions 29 and each be provided with an additional large recess 27 and small recess 28, two additional members identical with members 19 and 20 and two more additional members

identical with members 21 and 22 could be provided so as to form a puzzle having six vertical members, four horizontal members and six members transverse to the horizontal members. It is also to be understood that the corners of the component members may be beveled or rounded to give them a more pleasing appearance. These are but a few examples of the various ways in which the embodiment described specifically herein can be modified without departing from the spirit of the invention as defined in the following claims.

I claim:

1. A puzzle comprising four vertical members, 15 four horizontal members, and four members transverse to the horizontal members interlocking to form a symmetrical, self-sustaining unit, each of said members having two recessed portions shaped to interlock with the recessed portions of two other members, two of said members having cylindrical elements in both recessed portions and four of said elements each having a cylindrical element in one of the two recessed portions to allow rotation of the six last-named members relative to members engaged therewith.

2. A puzzle comprising four vertical members, four horizontal members, and four members transverse to the horizontal members interlocking to form a symmetrical, self-sustaining unit, each of said members having two recessed portions shaped to interlock with the recessed portions of two other members and at least some of said members having cylindrical elements in at least one of the recessed portions to allow rotation of said members relative to members engaged therewith.

3. A puzzle comprising twelve component members of equal length and cross-section, each of said twelve members having two recessed portions shaped to interlock with the recessed portions of two other members and said twenty-four recessed portions each having one of three different configurations, one of said configurations comprising a cylinder having its axis parallel to the axis of the member, said members interlocking with one another to form a symmetrical, self-sustaining unit.

ARTHUR HARRIS.
